US00D840341S

(12) **United States Design Patent** (10) **Patent No.:** **US D840,341 S**
Menolotto et al. (45) **Date of Patent:** **** Feb. 12, 2019**

(54) **CABLE CONNECTOR**

(71) Applicant: **Amphenol Corporation**, Wallingford, CT (US)

(72) Inventors: **Paolo Menolotto**, Mount Martha (AU); **Thien Huu Nguyen**, Springvale (AU)

(73) Assignee: **Amphenol Corporation**, Wallingford, CT (US)

(**) Term: **15 Years**

(21) Appl. No.: **29/608,244**

(22) Filed: **Jun. 20, 2017**

(51) LOC (11) Cl. **13-03**

(52) U.S. Cl.

USPC **D13/133**

(58) **Field of Classification Search**

USPC D13/133, 146, 147, 148, 151, 153, 154, D13/158, 173, 184, 199

CPC H01R 2103/00; H01R 9/053; H01R 13/00; H01R 13/627; H01R 13/6277

(57) **CLAIM**

The ornamental design for the cable connector, as shown and described.

DESCRIPTION

FIG. 1 is a front perspective view of a cable connector in accordance with a first embodiment of the present design; FIG. 2 is a front elevational view of the cable connector illustrated in FIG. 1;

FIG. 3 is a rear elevational view of the cable connector illustrated in FIG. 1;

FIG. 4 is a left side elevational view of the cable connector illustrated in FIG. 1;

FIG. 5 is a right side elevational view of the cable connector illustrated in FIG. 1;

FIG. 6 is a top plan view of the cable connector illustrated in FIG. 1; and,

FIG. 7 is a bottom plan view of the cable connector illustrated in FIG. 1.

The broken lines in the figures show elements of the article that form no part of the claimed design.

1 Claim, 7 Drawing Sheets
